UNITED STATES PATENT OFFICE

DAVID STARK, OF ARVERNE, NEW YORK

SHOE

Application filed November 12, 1928. Serial No. 318,703.

This invention relates to shoes, and provides improvements therein.

Many people in walking, very quickly run their shoes over at the side and destroy the shape of their shoes. This is particularly the case with women, particularly with light high-heeled shoes such as largely worn by them. Women, especially heavy women, will destroy the shape of a pair of shoes in a week, and will wear the soles through at the outer edge within two weeks.

This is due to initial wear at the heel combined with a careless way of walking, due either to habit or to weakness in the ankles. 15 The heel of the shoe instead of standing straight stands at an incline, the shoe twists in the shank, and all of the weight and wear are thrown at the outer side of the shoe, about under the little toe.

20 The present invention provides means for improving the conditions set forth above, incident to the use of shoes, providing shoes which give greater wear and keep their shape longer when worn by careless or improper walkers.

According to my invention, I make the shoe so that three points or spots on the sole and heel are joined so as to maintain said three points or spots in their original 25 position; that is, in the position of said spots, with relation to the plane of the ground or pavement, or floor, which said points or spots have when the shoe is new. This result is attained by providing the shoe with 30 a reinforcement between said three points, conveniently referred to as a tripod reinforcement. The reinforcement extends from the heel to a position about under the little toe of the foot of the user. Opposite the little toe the reinforcement does not extend 35 beyond the metatarsal portion of the foot, allowing bending of the toes on the inner side of the foot.

40 An embodiment of the invention is illustrated in the accompanying drawings, in connection with which the invention will be more fully described.

In said drawings,—

45 Figure 1 is a side elevation of a lady's

shoe showing in dotted lines application of the tripod reinforcement thereto.

Fig. 2 is a top plan view of the tripod reinforcement.

Fig. 3 is a longitudinal sectional view of the shoe and reinforcement shown in Fig. 1.

Fig. 4 is a plan view of a shoe following the inner sole of the shoe.

Figs. 5 and 6 are rear views of shoes.

Referring to said drawings, numeral 10 designates a shoe, here shown as a light woman's shoe, a type of shoe which readily loses its shape, especially when worn by heavy women, when the wearer does not walk properly.

Numeral 12 designates the outer sole, of usual construction, and numeral 14 the heel, which may be a wooden heel of usual construction fitted with a bottom or leather tip 15. Numeral 17 designates the inner sole, and numeral 20 the upper, which may be held between the inner sole and the outer sole in usual manner. Numeral 22 designates the insole lining.

Numeral 25 designates the part herein referred to as the tripod reinforcement. The part 25 is conveniently formed of metal, conforming to the shape of the insole. Part 25 extends under three points of the foot upon the ground, when standing. That is, it extends from a point or spot *a* under the heel to a point or spot *b* under the ball of the foot, and to a point *c* adjacent the little toe at the outer side of the foot.

The part 25 has the contour of the shoe and is placed in the shoe, and is preferably built therein, as here shown. The part 25 is conveniently located above the inner sole, and below the inner sole lining 22, so as to be covered thereby, and thereby preserving the ordinary appearance of the shoe.

The said part 25 is made stiffly resistant to torsion, so as to resist any change in the tripod points *a*, *b*, *c* of the shoe during use. That is, when a person walks on the outer side of their foot, for any cause, the heel wears on one side, as shown in Fig. 5, and shifts off to one side, so that in such a misshapen shoe the tripod points now have the position *a'*, *b*, *c*, Fig. 4.

The front part 27 of the plate is preferably attached to the shoe, and for this purpose may be provided with a plurality of small holes 29 through which nails may be driven into the sole and heel of the shoe and clinched.

In order to more rigidly reinforce the heel, the reinforcing part 25 may be provided with a projection 31 adapted to extend down into a suitable slot or opening formed in the heel. By means of this heel extension 31, the heel is maintained rigidly perpendicular to the plate or part 25.

As shown at 33, this extension 31 may be conveniently struck out of the part 25, and extends transverse of the shoe.

With a shoe provided with the present tripod reinforcement, the points of the tripod, as illustrated at points *a*, *b*, *c*, Fig. 4, are prevented from shifting when the wearer puts her foot down, heel first. If the wearer walks on the side of her foot, when the point *c* strikes the ground, the bearing is unstable, and the wearer's weight and instinct causes her to bring the shoe down so that there are three points of bearing on the ground, under the points *a*, *b*, *c* of the tripod. This action persists during the use of a shoe, and by preserving the relative position of the tripod points *a*, *b*, *c*, a shoe is prevented from getting into the misshapen condition shown in Fig. 5, and a shapely condition such as illustrated in Fig. 6 is preserved. The bending of the foot, as in walking is restricted only slightly, if at all, as the shoe from and forward of the ball of the foot on the big toe side is free to flex, the only effect of the stiffness of the sole under the little toe, being to force the user to bend the foot on the big-toe side, rather than on the little-toe side.

The wearing of shoes embodying the present invention not only preserves the shape of the shoe, but increases the life of the heel and the sole, as the wear is distributed more evenly over the heel and the sole, and, moreover, such a shoe has a corrective influence on persons who walk improperly or carelessly.

The invention may receive other embodiments than that herein specifically illustrated and described.

What is claimed is:—

1. A shoe having a tripod metal reinforcement in the bottom thereof of substantially the width of the shoe sole extending less than the length of the sole and from the heel to points at opposite sides of the sole, adjacent the little toe and adjacent the ball of the foot, the part adjacent the little toe being forward of the part adjacent the ball of the foot, said reinforcement by torsional resistance acting to counteract displacement of the heel of the shoe from its normal position in the tripod relation which it bears to two points in the sole under the little toe and under the ball of the foot.

2. A shoe having a tripod reinforcement in the bottom thereof of substantially the width of the shoe sole extending less than the length of the sole and from the heel to points at opposite sides of the sole, adjacent the little toe and adjacent the ball of the foot, the part adjacent the little toe being forward of the part adjacent the ball of the foot, and having a shank portion stiffly resistant to torsion, said reinforcement by torsional resistance acting to counteract displacement of the heel of the shoe from its normal position in the tripod relation which it bears to two points in the sole under the little toe and under the ball of the foot.

3. A shoe having a tripod reinforcement in the bottom thereof, said reinforcement comprising a metal plate of substantially the width of the shoe-sole, stiffly resistant to torsion, having a portion firmly attached to the heel of the shoe, and a sole portion less than the length of the sole of the shoe and having portions adapted to extend under the ball of the foot on one side and under a portion of the foot adjacent the little toe on the other side, the part adjacent the little toe being forward of the part adjacent to the ball of the foot, said reinforcement by torsional resistance acting to counteract displacement of the heel of the shoe from its normal position in the tripod relation which it bears to two points in the sole under the little toe and under the ball of the foot.

4. A shoe having a metal reinforcement in the bottom thereof of substantially the width of the shoe sole extending from the heel to a position adjacent the little toe on the little toe side, and extending forward a less distance on the opposite side, whereby the shoe is flexed more readily under the foot on the big toe side than on the little toe side, said reinforcement by torsional resistance acting to counteract displacement of the heel of the shoe from its normal position in the tripod relation which it bears to two points in the sole under the little toe and under the ball of the foot, thereby by correcting walking and preserving the shape of the shoe.

In witness whereof, I have hereunto signed my name.

DAVID STARK.
